UNITED STATES PATENT OFFICE

2,103,471

SPRING WIND-UP FOR WAGONS

Joseph Kuchar, Chicago, Ill., assignor to Athey Truss Wheel Co., Chicago, Ill., a corporation of Illinois

Application February 15, 1933, Serial No. 656,819

7 Claims. (Cl. 298—35)

This invention relates to a spring windup for wagons. According to the present invention, a spring windup is provided for wagons, which is adapted to close the doors thereof. The spring windup is particularly suitable for use in connection with a bottom dump wagon which comprises bottom doors adapted to open downwardly to dump the load. It is particularly applicable to such a bottom dump wagon in which the load 5 operates the doors in the downward direction and the spring windup operates them in the opposite direction. This invention is not intended to be limited to this particular kind of wagon, except in so far as set forth in the appended claims.

15 The invention will readily be understood from the following description of a preferred embodiment thereof, taken in conjunction with the accompanying drawings, in which

Figure 1 is a rear elevation of a wagon embodying my invention;

Fig. 2 is a side elevation thereof;

Fig. 3 is an elevational view on a larger scale, of the rear end of the wagon, the door closing mechanism being shown in section;

25 Fig. 4 is a sectional elevational detail taken on the line 4—4 of Fig. 3, and showing the hand-operated mechanism in elevation;

Fig. 5 is a similar more fragmentary view showing an operative position of the hand controls, 30 considerable structure being omitted for the sake of clearness;

Fig. 6 is a sectional plan detail view taken on the line 6—6 of Fig. 3;

Fig. 7 is a sectional detail view taken on the line 35 7—7 of Fig. 3;

Fig. 8 is a similar section taken on the line 8—8 of Fig. 3;

Fig. 9 is a diagrammatic view of pawls and ratchets when the doors are held closed, and

40 Fig. 10 is a similar view showing the relation of pawls and ratchets when the doors are held open.

Referring to the drawings, the reference numeral 11 designates the body of a bottom dump wagon which is supported on track laying wheels 12 of known type. The bottom of the wagon is constituted by doors 13 which are pivotally mounted at their outer edges. Each door 13 is provided with sheaves 14 on its underside, between which pass longitudinally lengths of a cable 15. The 45 sheaves 14 are located at the inner or meeting edges of the doors 13 and one is located at each end of the door 13. The cable 15 passes over a sheave 16 located at the front end of the wagon, this sheave receiving the center portion of the 50 cable.

The ends of the cable 15 pass upwardly at the rear of the wagon body passing over sheaves 17 mounted thereon, and said ends are secured to a drum 18. It will readily be seen that when the cable 15 is wound up on the drum 18, the doors 5 will close and the sheave 16 will provide equalization of the cable necessitated by irregularity of the cable ends upon the drum 18 or other causes, allowing both doors to be closed tightly. The structure so far described is well known and need 10 not be described minutely.

The drum 18 preferably comprises two halves 19 and 20, which are keyed or otherwise suitably mounted in rigid relation upon a drum shaft 21. Each half of the drum 18 is provided with means, 15 such as the clamps 22, for securing the ends of the cable 15 to the drum. The shaft 21 is mounted on bearings 23 and 24. The bearing 23 is supported by a casting 25 which is bolted or otherwise suitably secured to a channel section 26. 20 The bearing 24 is mounted in a housing 27 which is also bolted to the channel 26. The channel 26 is relatively wide and relatively short, extending only a part of the way across the end of the wagon. It is bolted to the rear end of the wagon, 25 being preferably secured to reenforcing angles 28, as shown in Fig. 3, so that a space 29 is left between the channel 26 and the rear wall 30 of the wagon. In this way the mechanism mounted in the channel is protected from misalignment or 30 jamming, resulting from isolated changes in the wall 30 due to extremely heavy loads, collisions with other machinery, etc. The outer end of drum element 20 is formed into a ratchet 31. Adjacent this ratchet and beyond the bearing 24, 35 the drum shaft 21 has keyed thereto a pinion 32. The other end of the shaft 21 has rigidly mounted thereon a ratchet 33, the teeth of which are directed oppositely to the teeth of the ratchet 31, as best seen in Figs. 4, 9 and 10. The ratchet 33 may be splined on the shaft 21 and is held thereon against longitudinal movement by means of collars 34 located on either side of the ratchet 33.

The housing 27 extends upwardly and encloses 45 a gear 35, which is rotatably mounted on a wall of said housing and is in mesh with the pinion 32. The gear 35 carries an integral outwardly directed sleeve 36 which is located within a cylindrical mouth 37 of the housing 27, which mouth is directed towards the right, as shown in Fig. 3. The sleeve 36 is provided with a bayonet slot 38 which receives an inwardly projecting hooked end of a helical spring 39. The other end of the spring 39 is similarly hooked and is 50 55

received within a bayonet slot 40 provided in a sleeve 41. This sleeve 41 is integral with an end member 42, which is circular in outline, its diameter being somewhat larger than the diameter 5 of the spring 39. The end member 42 is adapted to be received in a housing 43, which may form part of a casting 44 which is rigidly secured to the rear end of the wagon. The end member 42 comprises a nut portion 45 which projects through a suitable opening in the housing 43 so that it may be actuated by a wrench, to adjust the tension of the spring 39. The end member 42 comprises a flange which is provided with openings 46 around the periphery of the 15 end member 42. The housing 43 is provided with a corresponding opening 47 which is adapted to receive a pin 48 so as to hold the spring 39 in a desired state of tension. The spring 39 is enclosed by a cylindrical housing 49 which 20 projects into the mouth 37 of the housing 27 and into a similar oppositely directed mouth in the casting 44. These mouths are provided with felt washers 50 which serve to keep out dust and grit while permitting a certain amount of relative displacement between the housing 27, the casting 44 and the cylinder 49. This displacement is readily permitted by the spring 39, in view of the fact that no shaft or drum passes therethrough.

30 Ratchet 31 is adapted to cooperate with a pawl or dog 51 and ratchet 33 is adapted to cooperate with a pawl or dog 52. The relation of these pawls and ratchets is best shown in Figs. 9 and 10. Fig. 9 shows the condition when the doors are closed. In this condition the load in the wagon tends to pull the cables 15 so as to unwind the drum 18, that is, revolves it in a counter-clockwise direction, as viewed in Fig. 9. This tendency is opposed by the pawl 52 which is in engagement with the ratchet 33. At this time 40 the pawl 51 is out of contact with the ratchet 31. The relation of the pawls 51 and 52 and ratchets 31 and 33, which obtains after the doors are opened, is shown in Fig. 10. Here there is no load exerting a force against the wagon doors 45 and the spring 39 tends to rotate the drum in the clockwise direction, as viewed in Fig. 10. This rotation is prevented by the pawl 51 which is in engagement with the ratchet 31. The pawl 52 is out of engagement with the ratchet 33. The 50 means for controlling the pawls 51 and 52 will now be described.

The pawl 52 is pivotally mounted on a trip lever 53 which is located on the left-hand side of the drum 18, as shown in Fig. 1. At its lower 55 end the trip lever 53 carries a hand grip 54, and at its upper end it is provided with an enlarged head 55 which is keyed or otherwise secured upon a shaft 56. The shaft 56 is rotatably mounted in a bracket 57 which is bolted or otherwise secured upon the channel 26. The pawl 52 is pivotally mounted on a pin 58 which extends through lugs of the head 55.

It will be noted particularly in Fig. 4, that the trip lever 53, being pivotally mounted on the 60 axis of the shaft 56, and the axis of the pin 58 being located between the line joining the axis of the shaft 56 to the effective point of the pawl 52, it is necessary to raise the pin 58 or, in other words, rotate the trip lever in counter-clockwise 65 direction, as viewed in Fig. 4, in order to release the doors and allow the load to force them open. The amount of movement of the trip lever 53 necessary in order to open the doors, is controlled by a stop screw 59 which is adapted 70 to abut against the edge of the channel 26, as

shown in Fig. 4. Means are provided for holding the trip lever 53 in a normal position with the set screw 59 against this abutment. Such means preferably comprise a pin 60 pivotally mounted by means of a pin 61 upon the bracket 57 so that the pin 60 can rotate in a vertical plane parallel to the ratchet 33. The outer end of the pin 60 is threaded so as to receive a washer 62 and lock nut 63. The washer 62 serves as an outer abutment for a helical spring 64, 10 the inner end of which abuts against a collar 65 which is slidably on the pin 60. The collar 65 has outwardly projecting trunnions 66. The pin 60 and spring 64 is adapted to extend freely through an opening 67 in the head 55 of the 15 trip lever 53. Inwardly or forwardly of this opening the head 55 is provided with slotted extensions 67, within the slots of which the trunnions 66 are located. These trunnions are adapted to engage the extensions 67 at the forward 20 ends of the slots and thereby force the trip lever 53 forwardly into its normal position.

The shaft 56 is connected by means of a sleeve 68 to a shaft 69 which is rotatably mounted in a housing 70 which may suitably be integral with 25 the housing 27 previously referred to. Within the housing 70 an arm 71 is rigidly mounted on the shaft 69. At its free end the arm 71 carries a roller 72 which is adapted to engage a flange 73 of a lever 74. The lever 74 is pivotally mounted 30 by means of a shaft 75 in the housing 70, and carries the pivot pin 76 of the pawl 51. At its upper end the lever 74 has pivotally connected thereto a rod 77 which passes through an opening in a guide lock 78 in the housing 70, and is provided 35 therebeyond with a helical spring 79, abutment washer 80 and lock nuts 81. As shown in Fig. 7 the lock nuts 81 project through an opening 82 in the housing 70 so that the compression of the helical spring 79 may be adjusted at will. With reference to Fig. 7, it will be noted that the spring 79 40 serves to rotate the lever 74 in counter-clockwise direction and maintain the pivot pin 76 of the pawl 51 at a low position so that said pawl may engage the teeth of the ratchets 31. The lowermost 45 position of the pivot pin 76 is adjusted by means of a screw 83 which is mounted in a web 84, which may be integral with the housing 70.

It will be noted with relation to Figs. 9 and 10, that by pulling the trip arm 53 forwardly, the 50 pivots of both pawls 51 and 52 are elevated and the direction of rotation of the drum depends upon which force acting upon it is the stronger, that is, when the wagon is empty the spring will effect rotation of the drum in the clockwise direction, as shown in these figures, whereas if the wagon is loaded, the weight of the load will rotate the drum in the opposite direction. Assuming the doors to be shut and the wagon to be loaded, the relation of the pawls to the ratchets is shown 55 in Fig. 9. When the trip lever 53 is pulled forwardly the pivots of both pawls 51 and 52 are elevated. Pawl 51 is so configured that its ends move downwardly by gravity into contact with the teeth of the ratchet 31. When the pawls have elevated sufficiently, both pawls are carried through in a clockwise direction so that their points are directed to the left, as shown in Fig. 10. The relation of pawls shown in Fig. 10 is attained when the trip lever 53 is allowed to 70 return to its original position under the influence of spring 64. Assuming the doors to be open and the load to be dumped, then the pawls 51 and 52 are in the relation shown in Fig. 10. When the handle 53 is again moved forwardly the pivots of 75

the pawls 51 and 52 are both elevated and eventually they are carried through by the tension of the spring, which causes the ratchets 31 and 32 to rotate in the clockwise direction. When the handle 53 is released, the pawls return to the position shown in Fig. 9.

In the event of breakage of the spring I provide a hand lever 85. This hand lever has its end bifurcated and the ends are provided with elongated openings 86 through which pass the collars 34 of the shaft 21, the ends being located on either side of the ratchet 33. The hand lever 85 is provided with a tooth 87, which extends between the ends, which tooth 87 is adapted to be brought into contact with the teeth of the pinion 33 so that the drum may be wound up by hand by means of the hand lever. It is preferred to provide means whereby the lever 85 is removed from operative contact with the pinion 33, when the load is to be dumped. For this reason I provide on the lever 85 a contact member 88 and on the trip lever 53, I provide a cam surface 89 of such shape that it will engage the contact member 88 and move the lever 85 away from the ratchet 33 so that the tooth 87 is out of contact therewith. When this occurs the lever 85 falls by gravity to its normal position.

It is preferred to provide means which will enable the cams 51 and 52 to be actuated, in the manner described above, from a distance, for example, from the seat of a tractor to which the wagon is hitched, so that the dumping operation and the return of the doors may be effected without the tractor driver getting down from his seat. For this purpose I may mount a rod 90 along the side of the wagon, suitably guided in openings on the angle irons reinforcing the sides thereof. This rod may be connected to the tractor by means of a flexible cord or the like. The rear end of the rod 90 is secured to a short lever 91 which is rigidly mounted on a rod 92 rotatably mounted in a bracket 93 and in a bracket 94 mounted on the channel section 26, adjacent the ratchet 33.

Adjacent the bracket 94, the rod 92 has mounted thereon a rearwardly projecting arm 95. To the arm 95 is pivotally mounted a link 96, which projects upwardly and is pivotally mounted at its upper end to a boss 97 on the head 55. It will readily be seen that when the rod 90 is pulled forwardly, the rod 92 is rotated so as to elevate the outward end of the arm 95 and the link 96 causing the elevation of the head 55 of the trip arm 53 about its pivot 56, this movement having the effect of raising the pivots of the pawls 51 and 52 with the results described above, depending upon the condition of load and door opening prevailing.

If desired, the mechanism described above may readily be made over into a hand-operated device. For this purpose the housings 43 and 27 are removed, together with all the mechanism therein, likewise the sleeve 68. The drum member 29 may or may not be removed, as desired. If it is removed it may be replaced by an element similar to element 19, that is, one without the ratchet 31. The right-hand end of the shaft 21, as viewed in Fig. 3, is provided with a suitable bearing which is bolted to the channel member 26. Thus altered, the device will operate in the following manner: On moving the trip lever 53 outwardly, which may be done by hand directly or may be done through the remote movement of the rod 90, the doors will be released and the load will force them open. To close the doors, the trip lever 53 is again

moved forwardly which has the effect of permitting the pawl 52 to move into operative relation with the ratchet 33, this movement being effected by gravity owing to the shape of the pawl and the manner in which it is weighted. The trip lever 53 is allowed to return to its normal position and the handle 85 can be operated to rotate the drum and close the doors, as described above.

Although the invention has been disclosed in connection with the specific details of a preferred embodiment thereof, it must be understood that such details are not intended to be limitative of the invention except in so far as set forth in the accompanying claims.

Having thus described my invention, what I claim as new and desire to secure by Letters Patent of the United States is:

1. A spring windup for wagons adapted to operate wagon doors, comprising a drum adapted to receive flexible members, bearings for said drum, a pinion on said drum, a gear in mesh with said pinion, a bearing for said gear, a base on which said bearings are mounted, said base being mounted on the wagon wall, a helical spring, one end of which is secured to said gear, an end member operatively secured to said spring, means rigidly securing said end member to said wall, and releasable means adapted to hold said drum against rotation in both directions.

2. A spring windup for wagons adapted to operate wagon doors, comprising a drum adapted to receive flexible members, bearings for said drum, a pinion on said drum, a gear in mesh with said pinion, a bearing for said gear, a channel member on which said bearings are mounted, said channel member being mounted on the wagon wall, a helical spring, one end of which is secured to said gear, an end member operatively secured to said spring, a housing mounted on said wall rotatably receiving said end member, and means for securing said end member against rotation in said housing to maintain the tension of the spring at a desired degree, and releasable means adapted to hold said drum against rotation in both directions.

3. A spring windup for wagons adapted to operate wagon doors, comprising a drum adapted to receive a flexible member whereby it may be rotated in one direction, a spring adapted to rotate the drum in the opposite direction, a pair of oppositely directed ratchets on said drum, a pawl cooperating with each ratchet and pivotally mounted, each pawl being counterweighted so that it tends to direct return by gravity to its operative position with its point toward its ratchet, one pawl being normally in operative engagement with its ratchet and the other being out of operative engagement with its ratchet, and a pivoted frame for elevating the pivotal supports of the pawls simultaneously away from the ratchets to permit the pawl in operative position to be drawn by its ratchet into inoperative position and permit the pawl in the inoperative position to return to its operative position.

4. A spring windup for wagons adapted to operate wagon doors, comprising a drum, flexible means connecting same to said doors whereby the weight of the load tends to rotate the drum in one direction, a spring adapted to rotate the drum in the opposite direction, and a pair of oppositely directed ratchets on said drum, a free-swinging pawl associated with each ratchet and conformed counterweighted so that its operative point is biased by gravity towards oper-

ative engagement with its ratchet, rocking means adapted to raise the pivotal axes of said pawls away from the ratchets, whereby the drum rotating in one direction carries the operative pawl 5 with it into inoperative position and carries the non-operative pawl into its operating position.

5. A spring windup for wagons adapted to operate wagon doors, comprising a drum adapted to receive a flexible member whereby it may be rotated in one direction during the opening of the doors, a spring adapted to rotate the drum in the opposite direction to close the doors, a pair of oppositely directed ratchets rigidly associated with said drum, a pawl cooperating with each 10 ratchet, a swinging frame upon which one pawl is pivotally mounted, an arm on which the other pawl is pivotally mounted, each pawl being counterweighted so that it tends to return by gravity to operative position with its point towards its 15 ratchet, one pawl being normally in operative engagement with its ratchet and the other being out of operative engagement with its ratchet, means for swinging the frame so as to elevate the pawl mounted thereon, and means on the frame 20 cooperating with said arm to elevate the other pawl simultaneously whereby the pawl in operative position may be drawn by its ratchet into inoperative position and the pawl in the inoperative position permitted to return to its operative 25 position.

6. A spring windup for wagons adapted to operate wagon doors, comprising a drum adapted to receive a flexible member whereby it may be rotated in one direction during the opening of 30 the doors, a spring adapted to rotate the drum in the opposite direction to close the doors, a pair of oppositely directed ratchets rigidly associated with said drum, a pawl cooperating with each ratchet, a swinging frame upon which one 35 pawl is pivotally mounted, an arm on which the other pawl is pivotally mounted, each pawl being

counterweighted so that it tends to return by gravity to operative position with its point towards its ratchet, one pawl being normally in operative engagement with its ratchet and the other being out of operative engagement with its ratchet, means for swinging the frame so as to elevate the pawl mounted thereon, means on the frame cooperating with said arm to elevate the other pawl simultaneously whereby the pawl in operative position may be drawn by its ratchet 10 into inoperative position and the pawl in the inoperative position permitted to return to its operative position, and adjustable means independent of the swinging frame for limiting the downward movement of said arm. 15

7. A spring windup for wagons adapted to operate wagon doors, comprising a drum adapted to receive a flexible member whereby it may be rotated in one direction during the opening of the doors, a spring adapted to rotate the drum in the opposite direction to close the doors, a pair of oppositely directed ratchets rigidly associated with said drum at opposite ends thereof, a pawl cooperating with each ratchet, a swinging frame upon which one pawl is pivotally mounted, an arm on which the other pawl is pivotally mounted, each pawl being counterweighted so that it tends to return by gravity to operative position with its point towards its ratchet, one pawl being normally in operative engagement with its ratchet 20 and the other being out of operative engagement with its ratchet, means for swinging the frame so as to elevate the pawl mounted thereon, and means on the frame cooperating with said arm to elevate the other pawl simultaneously, said frame extending from one end of the drum to the other, whereby the pawl in operative position may be drawn by its ratchet into inoperative position and the pawl in the inoperative position permitted to return to its operative position. 25

JOSEPH KUCHAR.
